UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

SIGNAL FOR SECTIONAL CONDUCTORS.

No. 806,638.

Specification of Letters Patent.

Patented Dec. 5, 1905.

Application filed May 21, 1904. Serial No. 209,109.

To all whom it may concern:

Be it known that I, FRANK E. CASE, a citizen of the United States, residing at Schenectady, in the county of Schenectady and State 5 of New York, have invented certain new and useful Improvements in Signals for Sectional Conductors, of which the following is a specification.

My invention relates to electric railways 10 employing sectional conductors; and its object is to prevent a train from spanning between a section which is dead or grounded and a live section.

It is common practice to equip an electric 15 railway with a sectional conductor, such as sectional third rail, the several sections being connected to the source of power independently of each other, so that an accident to one section will not shut down the entire 20 road. The collecting-shoes usually employed on third-rail systems are of sufficient length to span from one section to another, and consequently when one section is grounded there is danger unless safeguards are provided that 25 the train will pass from a live section to a grounded section, thereby opening the circuit-breaker or blowing the fuse on the live section and cutting it out of circuit. In order to prevent this, it has been suggested heretofore 30 to employ a signal at the entrance to each section, the signal being connected to show whether the section is dead or alive. This furnishes sufficient protection against 35 the train entering the dead section from a live one, but it does not provide against the following contingency: It is possible that a section may become grounded while a train is on that section, and if the motorman has the power shut off and the train is coasting 40 he will receive no indication that the section has become grounded and dead. If he allows his train to coast onto the following section which is alive, the section which he is entering will be short-circuited through the one 45 which he is leaving.

My invention consists in guarding against this contingency by providing at the junction of each two sections a signal which shall give the proper indication if either or both of the 50 two sections is dead or grounded. In this manner a train is prevented from passing

either from a live section onto a dead section, or vice versa.

My invention will best be understood by reference to the accompanying drawings, in 55 which—

Figure 1 shows diagrammatically a system of signals for sectionalized third rail arranged in accordance with my invention, and Fig. 2 shows a modified form of signal.

In Fig. 1, R R represent the rails of an electric road the power for which is supplied through the sections T, T', and T² of a third rail. The several sections are connected to the generator or power station G through the 65 switches s, s', and s² and their respective feeders. C C represent the collector-shoes carried by a moving train and adapted to engage the sections of the third rail. M represents a magnet-winding having one terminal 70 connected to the section T and its other terminal connected to earth through the armature of the relay m, the winding of which is connected between the section T' and earth. A represents a signal-arm which is held in 75 the "safety" position as long as the magnet-winding M is energized. With this arrangement it will be seen that if either section T or T' becomes grounded or is cut out from the power-station the magnet-winding M will be 80 deenergized and will allow the signal-arm A to fall to "danger," thereby giving indication that one of the two sections is dead.

Many different forms of signal-controlling devices may be used other than that shown. 85 The two magnet-windings may be combined in a single mechanism—as, for instance, in a differential solenoid or a device of the wattmeter type. The latter is shown diagrammatically in Fig. 2. Stationary winding N 90 is connected between section T and earth, while the movable winding n, which carries the signal-arm A, is connected between section T' and earth. A deenergizing of either of the two windings will allow the signal-arm 95 A to drop.

Although I have shown a simple signal-arm operated by the electroresponsive mechanism, it is evident that any other well-known form of signal, such as a brake-applying device, may be employed, if desired, and I aim in the appended claims to cover all such 100

modifications which are within the spirit and scope of my invention.

What I claim as new, and desire to secure by Letters Patent of the United States, is—

- 5 1. In combination with a sectional conductor, magnet-windings connected to adjacent sections of said conductor, and a signal controlled by said windings and operative upon a deenergizing of either winding.
- 10 2. In combination with a sectional conductor, an electroresponsive signaling device having windings connected to adjacent sections of said conductor and operative upon a deenergizing of either of said windings.
- 15 3. In an electric railway, a sectional third rail, and an electroresponsive signaling device having windings connected to adjacent sections of said third rail and operative upon a deenergizing of either or both of said windings.
- 20 4. In an electric railway, a sectional third rail, and an electroresponsive signaling device connected to adjacent sections thereof and operative upon a deenergizing of either of said sections.
- 25 5. In an electric railway, a sectional third rail, and an electroresponsive signaling device having two windings connected respec-

tively between adjacent sections of said third rail and the opposite polarity of the system 30 and operative upon a deenergizing of either or both windings.

6. In combination with a sectional conductor, a source of current-supply, means for connecting the sections of said conductor to one 35 terminal of said source of supply, an electrical connection between each of a plurality of sections and the other terminal of said source of supply, a signal, and an electromagnetic controlling apparatus for said signal having 40 a winding in each of said latter connections.

7. In an electric railway, a sectional third rail, a source of current-supply, means for connecting the sections of said third rail to one 45 terminal of said source of supply, electrical connections between each of two adjacent sections and the other terminal of said source of supply, a signal, and an electromagnetic controlling apparatus for said signal having a winding in each of said latter connections. 50

In witness whereof I have hereunto set my hand this 20th day of May, 1904.

FRANK E. CASE.
